THREAD GUIDE FOR CONE OR TUBE
WINDING MACHINESEdgar S. Kennedy, Norristown, Pa., assignor, by
mesne assignments, to American Viscose Cor-
poration, a corporation of Delaware

Application June 1, 1935, Serial No. 24,555

11 Claims. (Cl. 242—157)

This invention relates to thread guides for cone or tube winding machines, and has for its principal object to prevent yarn catching upon exposed metal parts of the supporting structure for the guide.

Other objects are to provide an improved mounting for the guide and to provide a guide which will free itself from any loops which may be formed around the guide.

10 Further objects may become apparent from the following description and the accompanying drawing, in which:

Figure 1 is a side elevation of a conventional winding mechanism, with parts broken away to

15 show the novel thread guide mounted thereon;

Figure 2 is an end elevation of Figure 1;

Figure 3 is a face view of the thread guide;

Figure 4 is a vertical section taken along the line 4—4 of Figure 3;

20 Figure 5 is a reverse view of Figure 3;

Figure 6 is a detail of the spring clip;

Figure 7 is an exploded view of the guide supporting parts;

Figure 8 is an elevation of the supporting arm; 25 and

Figure 9 is a vertical section through the guide as mounted on the supporting arm.

The portions of the conventional winding ma-

30 chine shown in Figures 1 and 2 comprise a spin-

dle 10 adapted to receive a cone center 11, such

35 as a cone or other core for a yarn package 12.

A weighted lever 13 is pivoted below the spindle, and has a groove in its upper end receiving a

traverse bar 14, which is reciprocated by a cam

40 arrangement (not shown). A supporting metal

arm 17 has a foot 18 secured to the traverse bar,

a retaining tongue 19 therefor, and an upper

end on which is mounted a yarn guide 20.

This thread or yarn guide 20 comprises a block

45 of material having a low coefficient of friction, such for example as porcelain, with a convex bearing surface to rest against the cone center

11 or the package 12 wound thereon, and is pro-

vided with a yarn guiding eye 21 extending

45 through the center of the convex surface. A

thread guide of this character is known in the

art and is illustrated for example in the Mitchell

Patent No. 883,116, March 24, 1908.

According to the present invention, the upper

50 end of the supporting arm 17 is buried or embed-

ded in the porcelain of the guide, so that no metal

is exposed for the yarn to catch upon. The re-

verse side of the guide has a concave depression

55 22 therein and a central boss 23 forming an an-

5 arcuate fingers 25 which lies in the groove 24 and embrace the boss 23.

A transverse slot 26 is formed in the base of the guide and extends upwardly therein, terminating in branches 27 extending one on each side 5 of the boss 23. A spring clip 28 is adapted to enter the slot 26 and has arcuate fingers 29 lying in the branches 27. The lower end of the spring clip 28 is offset to lie against the arm 17, to which it is secured by screws 30, thus rigidly and se- 10 curely clamping the guide 20 thereto, without necessitating the use of shellac or the like.

The yarn guiding eye 21 as shown is triangular in vertical cross section and diverges horizontally toward the winding mechanism. The guide is 15 provided with a vertical slot 31 communicating with the eye 21, and the surfaces 32 of the guide adjacent to the slot are flared outwardly therefrom, for convenience in threading the eye.

The yarn passes to the eye over a bail 33 which 20 prevents it from passing below the plane of the eye on that side. On the other side, the contact of the guide with the face of the yarn already wound prevents the yarn from passing below the plane of the eye, which may be designated as the 25 yarn level. Hence the yarn can only move upward or to one side of this yarn level.

It should be noted that there are no exposed 30 metal parts of the guide above the yarn level, and that all sides of the guide converge above the yarn level. Hence there is nothing on which the yarn may catch, and furthermore any loop which may happen to be formed around the guide will free itself due to the converging sides.

There is no opportunity for the loops to catch 35 upon this guide, and actual operation has demonstrated that the presence of any loops on the cone, due to chattering tension grid or slack yarn when starting the spindle, is not harmful.

From the foregoing description it will be read- 40 ily apparent that the guide according to the present invention is easier to thread, has the spring clip buried, particularly above yarn level, is fixed to the holder more firmly and without the use of shellac, is absolutely rigid, has no junc- 45 tion points of metal to porcelain to catch thread, and has the tapered sides of the guide to prevent loops catching thereon.

What I claim is:

1. A thread guide having a convex bearing sur- 50 face adapted to rest against the thread on a ro-
tating winding mechanism and provided with an eye extending through substantially the center of said convex surface, said guide having a vertical slot communicating with said eye whereby thread 55

may be inserted therein laterally and whereby shoulders are formed to retain said thread, the sides of said slot above said shoulders being flared outwardly to facilitate said thread insertion, and

5 the sides of said guide above said eye being tapered inwardly toward the top whereby a loop of thread caught thereon may free itself.

2. A thread guide having a convex bearing surface adapted to rest against the thread on a rotating winding mechanism and provided with a thread guiding eye extending through substantially the center of said convex surface, a supporting arm having an end embedded in said guide, said guide having in its base a slot extending up within said guide and terminating in branches entirely inside of said guide and on each side of said eye, and means in said slot for securing said guide to said arm.

3. A thread guide having a smooth surface 20 adapted to engage the thread on a rotating winding mechanism and provided with a thread guiding eye extending through said surface, a supporting arm and a clamping member both embedded in said guide, an internal portion of said 25 guide extending between said supporting arm and said clamping member, and means for drawing said clamping member and said arm toward each other to clamp said internal portion therebetween.

30 4. A thread guide having a convex bearing surface adapted to rest against the thread on a rotating cone or tube winding mechanism and provided with an eye extending substantially through the center of said convex surface, in combination with means whereby said mechanism prevents the yarn from passing below said eye, the sides of said guide above said eye being tapered inwardly whereby a loop caught thereon may free itself, a supporting arm having a portion sunk into said guide and covered by said 35 tapered sides, and a clip member having a portion secured in a slot in said guide, an internal portion of said guide extending between said supporting arm and clip member, and means for drawing said supporting arm and clip member 40 toward each other to clamp said internal portion therebetween.

5. A thread guide having a convex bearing surface adapted to rest against the thread on a rotating winding mechanism and provided with a thread guiding eye extending through substantially the center of said convex surface, and a supporting metal arm having an attaching means 50 extending into and covered by said guide between said arm and said surface, whereby said guide guards the thread against contacting said attaching means.

6. A thread guide having a smooth surface 60 adapted to engage the thread on a rotating winding mechanism and provided with a thread guiding eye extending through said surface the reverse side of said guide having a concave depression with a central boss, a supporting arm having an end projecting into said depression and terminating in fingers extending around the sides of said boss, said guide having in its base a slot 65 extending up within said guide and terminating

in branches on each side of said eye, and means in said slot for securing said guide to said arm, whereby said guide guards the thread from contacting said arm.

7. A thread guide having a smooth surface 5 adapted to engage the thread on a rotating winding mechanism and provided with a thread guiding eye extending through said surface, said guide having a slot below said surface, the rear of said guide having a depression, a supporting arm 10 engaging said depression, a clip engaging said slot, and means outside of said guide for rigidly securing said clip to said arm and drawing the guide engaging parts together to clamp the internal portion of the guide therebetween.

8. A thread guide having a smooth external surface and an eye extending through said surface, a supporting arm engaging a portion of said guide, an attaching member engaging an internal surface of said portion, and means 20 co-operating with said arm and member to secure them together outside of said guide whereby a rigid mounting is provided, said cooperating means exerting pressure sufficient to cause clamping action of said arm and member upon 25 said portion of said guide between said arm and member.

9. A thread guide having a smooth convex surface adapted to engage the thread on a rotating winding mechanism and provided with a thread 30 guiding eye extending through substantially the central portion of said convex surface, a supporting arm engaging an internal portion of said guide, an attaching member engaging another internal portion of said guide, means cooperating 35 with said arm and guide for clamping said internal portions of said guide therebetween, said co-operating clamping means including threaded means for preventing relative rotation of said arm and member.

40 10. A thread guide having a convex bearing surface adapted to rest against the thread on a rotating winding mechanism and provided with a thread guiding eye extending through said surface, said guide having in its base a mortise extending up within said guide, in combination with a supporting metal arm for said guide, and means 45 cooperating with said guide and arm for securing the same together comprising a tenon entering said mortise, and means rigidly securing said 50 tenon to said arm outside of said guide and causing said tenon to press against one side of said mortise, and said arm to press against opposite parts of said guide, to clamp internal portions of said guide therebetween.

55 11. A thread guide having a smooth surface adapted to engage the thread on a rotating winding mechanism and provided with a thread guiding eye extending through said surface, and means for mounting said guide comprising a jaw 60 engaging the rear surface of said guide, a second jaw extending into the inside of said guide in front of the first jaw, and means for securing said jaws together to effect a clamping action on the internal portions of said guide therebetween.
